(57) **CLAIM**

(21) Appl. No.: **29/309,599**

The ornamental design for an aircraft seat, as shown and
described.

(30) **Foreign Application Priority Data**

Mar. 19, 2008 (JP) D2008-006843

DESCRIPTION

FIG. 1 is a perspective view of an aircraft seat showing our
new design;

FIG. 2 is a front elevational view thereof;

FIG. 3 is a rear elevational view thereof;

FIG. 4 is a right side elevational view thereof;

FIG. 5 is a top plan view thereof; and,

FIG. 6 is a bottom plan view thereof.

FIG. 7 is a left side elevational view thereof; and,

Portions of FIGS. 1–5 that are shown as broken lines are for
illustrative purpose only and form no part of the claimed
design.

FIG. 7 is for illustrative purposes only and forms no part of the
claimed design.

See application file for complete search history.
